SASH LOCK

Axel W. Ahlgren, Rockford, Ill.

Application April 21, 1958, Serial No. 50,546

Term of patent 14 years

(Cl. D10—10)

Figure 1 is a perspective view of a sash lock showing my new design.

Fig. 2 is a top plan view.

Fig. 3 is a rear view of the sash lock.

Fig. 4 is a side view taken on a smaller scale.

Fig. 5 is an enlarged fragmentary sectional view of the separable parts taken along the line 5—5 in Fig. 2.

I claim:

The ornamental design for a sash lock, substantially as shown.
